OUTRIGGER OR SIMILAR ARTICLE

Roger A. Spindler, Westfield, N.J., assignor to August Spindler & Sons, Inc., Cranford, N.J., a corporation of New Jersey

Filed Nov. 12, 1964, Ser. No. 82,573

Term of patent 14 years

(Cl. D41—1)

FIG. 1.

FIG. 2.

FIG. 3.

FIG. 1 is an elevational view of one side of an outrigger or similar article embodying my new design, the other side thereof being identical;

FIG. 2 is a front elevational view as seen from the right of FIG. 1 with the sleeve in vertical position.

FIG. 3 is a top plan view thereof.

I claim:

The ornamental design for an outrigger or similar article, as shown and described.
